CLAIM

The ornamental design for a hand held tool, as shown and described.

DESCRIPTION

FIG. 1 is a top plan view of a hand held tool in accordance with my design;

FIG. 2 is a top, front, right perspective view thereof;

FIG. 3 is a bottom view thereof;

FIG. 4 is a bottom, rear, left perspective view thereof; and

FIG. 5 is an elevational view thereof;

FIG. 6 is a top plan view of a second embodiment of a hand held tool in accordance with my design;

FIG. 7 is a top, front, right perspective view thereof;

FIG. 8 is a bottom view thereof;

FIG. 9 is a bottom, left, rear perspective view thereof; and,

FIG. 10 is an elevational view thereof.

The broken lines depict portions of the hand held tool that form no part of the claimed design.
